UNITED STATES PATENT OFFICE.

HANS ALBERT PHILIPS, OF STRATFORD, CONNECTICUT, ASSIGNOR TO THE AMERICAN FABRICS COMPANY, OF BRIDGEPORT, CONNECTICUT, A CORPORATION OF CONNECTICUT.

GIRDLE.

Application filed May 17, 1923. Serial No. 639,560.

To all whom it may concern:

Be it known that I, HANS ALBERT PHILIPS, a citizen of the United States, residing at Stratford, county of Fairfield, State of Connecticut, have invented a new and useful Girdle, of which the following is a specification.

This invention relates to a girdle or similar article and especially to the construction 10 of a tassel at the end of a cord, that is a girdle cord, and has for an object to provide an improved tassel which may be manufactured at low cost, which will be simple in construction, and which, when completed, 15 will be neat and attractive in appearance and not likely to be easily pulled apart.

With the foregoing and other objects in view I have devised the construction illustrated in the accompanying drawing, in 20 which—

Fig. 1 is a side elevation of one end of a braided girdle prior to the application of the tassel thereto.

Fig. 2 is a partial side elevation and partial sectional view substantially at right angles to Fig. 1, showing the tassel partly completed.

Fig. 3 is a partial sectional and partial side elevation showing the completed tassel, 30 and

Fig. 4 is a side elevation showing the completed tassel.

In forming the girdle any suitable cord may be used but I prefer the construction 35 shown in which a plurality of strands 10, preferably 3, are braided to form the cord, and each strand preferably consisted of a number of independent threads or small cords. The tassels are formed on the ends 40 of the cord and in a completed girdle there will be a tassel at each end.

In forming this tassel the strands adjacent the free ends thereof are left slightly loose and secured together as by tying, as shown 45 at 11. The ornament or button 16 is then slipped onto the cord, as shown in Fig. 1, with the free end of the cord extending below the same. The tuft 12 is then applied to the cord. The tuft 12 of the tassel consists of a bundle of threads looped at one end as at 13 and tied together at the other end as at 14. In applying this tuft to the cord or the girdle the cord is opened above the tie 11, as shown at 15, and the tied end

14 of the tuft is passed through this opening and pulled down so that the ends of the tuft on opposite sides of the girdle are substantially even or the same length. The tuft is then securely fastened to the cord by sliding the ornamented tubular button 16 down over the tuft and the end of the cord where the tuft passes through the same, as shown in Figs. 3 and 4. This button may be of any construction but in the form shown comprises a suitable body 17 of 55 wood or similar material covered with an ornamental cloth covering 18. After this button or ornament has been placed in position, as shown in Figs. 3 and 4, the tie 14 and the loops at 12 are cut completing the 60 tassel and providing the usual free ends for the cords or threads in the tuft. 70

It will be apparent from the foregoing description that the tassel is very simple in construction and is easily formed. Also that 75 it requires a minimum of material, with a single ornament or button forming the head and at the same time securing the tuft to the cord. It will also be apparent that the manual operations are simple and may be 80 easily and quickly performed, greatly reducing the cost of the tassel. It will still further be apparent that the completed tassel is neat and attractive in appearance. 85

Having thus set forth the nature of my invention, what I claim is:

1. In an article of the class described, braided strands, means for tying the strands together adjacent the ends thereof, a tuft of loose threads or cords threaded through the 90 braided portion inwardly of the tying means and finishing means embracing the tuft threads or cords at the point where they are threaded through the braided portion.

2. In an article of the class described, a 95 cord comprising a plurality of strands, means for securing the strands together adjacent the ends thereof, a tuft of threads extending through the cord inwardly of the securing means, and finishing means embracing the threads adjacent the point where they extend through the cord. 100

3. In an article of the class described, a 105 cord comprising a plurality of strands, means for securing the strands together adjacent the ends thereof, a tuft of threads extending through the cord inwardly of the securing means, and a tubular button embrac-

ing the threads and the cord at the point the threads extend through the cord.

4. In an article of the class described, a cord comprising a plurality of braided strands, 5 means for tying the strands together adjacent their free ends, a tuft of loose threads extending through the cord inwardly of said tying means, and a tubular button embracing the tuft and the cord at the point 10 the tuft extends through the cord.

5. The method of making a tassel on a cord which consists in securing the strands of the cord together adjacent their free ends, tying together one end of a tuft of loose 15 threads and passing it through the cord above the securing means, sliding a tubular button

over the tuft at the point it extends through the cord, and cutting the tie on the tuft.

6. The method of making a girdle which consists in braiding a plurality of strands 20 of threads, tying the strands together adjacent the ends thereof, tying one end of a bundle of threads and passing this tied end through the cord inwardly of the tie to form the tuft of a tassel, sliding a tubular button 25 over the bundle of threads to embrace the same and the cord at the point the threads pass through the cord to form a head for the tassel, and removing the tie on the bundle of threads. 30

In testimony whereof I affix my signature.

HANS ALBERT PHILIPS.
